[57] ABSTRACT

A device adapted to carry a coil of wire or the like includes a cylindrical ring having an outside diameter about the same as the inside diameter desired for the coiled material, at least one radial projection extending outwardly from one end of the ring a distance sufficient to support the coil thereon, and a handle connected to the ring and adapted to carry the device and the coiled material thereon. The device is particularly effective for carrying coils of barbed wire. Despite the fact that only a fraction of a coil of barbed wire is supported directly by the cylindrical ring and radial projection, the layers of the coil do not sag because of their mutual coherence and adequately support the coil. In producing the coiled material the device may be mounted on the winding mandrel of a winding machine.

DEVICE FOR CARRYING COILED MATERIAL SUCH AS A COIL OF BARBED WIRE

BACKGROUND OF THE INVENTION

1. Field of the Invention

The present invention relates to apparatus for carrying a coil of wire, cable or strapping material, such as barbed wire, to a coil of such material wound around such apparatus and to a method for coiling up material on such apparatus.

2. Description of the Prior Art

Wire coils, such as coils of barbed wire, are normally wound on a spool (which itself may be made of metal wire) provided with a handle to facilitate the manipulation of the wire coils. A handle is particularly necessary in the case of coils of barbed wire so as to prevent the barbs from causing injuries. However, the design of conventional spools is such that a substantial amount of undesirable extra weight is added to the coils of material.

SUMMARY OF THE INVENTION

The present invention is embodied in a device adapted to carry a coil of wire or other coilable material which includes a cylindrical ring having an outside diameter about the same as the inside diameter of the coil, at least one radial projection extending outwardly from one end of the ring a distance sufficient to support the coil thereon, and a handle connected to the ring and adapted to carry the device.

It is an object of the present invention to provide a light-weight and stable carrying device for a coil of wire or other coilable material, such as barbed wire.

It is a further object of the present invention to provide an improved coil of wire or other coilable material, such as barbed wire, in combination with a convenient and simple carrying device.

It is a still further object of the present invention to provide a simple and effective method for winding a coil of wire or other coilable material, such as barbed wire, on a coil support means.

Other objects and advantages of the present invention will become apparent from the following description taken in conjunction with the accompanying drawings.

BRIEF DESCRIPTION OF THE DRAWINGS

FIG. 1 is a perspective view of a coil carrying device embodying the present invention;

FIG. 2 is a perspective view of a coil of barbed wire supported on the device shown in FIG. 1;

FIG. 3 is a side view in partial section of the coil of barbed wire shown in FIG. 2, resting on a supporting surface;

FIGS. 4a and b are respectively a modification of the device shown in FIG. 1 and a repetition of the device shown in FIG. 1;

FIG. 5 is an enlargement of a portion of the device shown as encircled in FIG. 4b; and

FIG. 6 is an enlargement of a portion of the device shown as encircled in FIG. 4a.

DESCRIPTION OF THE PREFERRED EMBODIMENTS

As shown in FIG. 1, the carrying device embodying the present invention includes a cylindrical ring 11, around which a coil of barbed wire 12 may be wound,

and a handle 13. The ring 11 is provided at its bottom side with a radially projecting ring flange 14 and at its upper side with axial lips or projections 15 to which handle 13 is fixed. The handle 13 consists of a U-shaped piece of wire having two legs 16 and a base 17. The free ends of the legs 16 are bent to the outside and engage with pre-tension from the inside through openings in the projections 15. The wire of the handle 13 may be coated with a protective layer of synthetic material. The length of the base 17 between the legs 16 approximately corresponds to the inside diameter of the central opening 18 of the coil of barbed wire 12 as shown in FIG. 2.

As can be seen in FIG. 3, the axial length or height 15 of the cylindrical ring 11 corresponds to the height of a layer of a few windings of the wire coil 12. The length or width of the radial projection of the ring flange 14 is normally designed in such a way that the flange 14 engages between adjacent windings of the wire at the 20 open inside surface of coil 12. Instead of a circular ring flange, or as an extension thereof, radial projections may be fixed at spaced points on the outer side of the ring.

FIGS. 4a and 6 show a modification of the device of 25 the present invention in which the outer surface of the ring is provided with spaced projections 19, 20 and 21 in addition to the ring flange 14. The ring flange 14 is also provided with a radially projecting lip 21 under the projection 20. The radial projections 19 and 21 provide 30 a reinforcement of the ring 11 and in addition provide particular points of contact on which the windings of barbed wire exert a lateral pressure and through which extra tension originates as an aid to prevent the windings from slipping off.

35 As can be seen particularly in FIGS. 2 and 3, the ring 11 is located in the central bore 18 in such a way that the top edge of the ring and the top surface of the coil are essentially at the same level with the lips 15 which are provided for attaching the handle projecting thereabove. The hinge joints are thus located free from the 40 coil of barbed wire, so that the handle 13 can be freely swung down on the upper plane of the coil, as can be seen in particular in FIG. 3.

The ring 11, the ring flange 14 and the projections 45 such as 15 normally will be made in one piece and, preferably, of a synthetic material such as a plastic (e.g. polyethylene).

When piling up a number of coils, the collapsible 50 handle may also be used to improve the stability of the pile, namely by positioning the handle upright and having it engaged in the central bore of the coil immediately thereabove. The coils are preferably piled up in such a way that the plane of the handle of an underlying coil is in each case perpendicular to the plane of the handle of the coil placed thereupon.

A typical coil of barbed wire would have, say, an outside diameter of approximately 30 to 40 cm, an inside diameter of approximately 10 to 12 cm and a height of 55 approximately 20 to 30 cm. In such a case, the axial length of the ring 11 or the carrying device would preferably measure about 2cm, the radial width of the ring flange would be approximately 0.3cm and the thickness of the ring material would be approximately 0.3cm. In practice, a light weight material is normally entirely suitable for the bearing ring.

When using a ring of the type shown in FIGS. 4a and 6, no upward projecting lips (e.g. lips 15) need be em-

ployed for engaging the legs 16 of the handle 13, since two especially designed ribs 20 fixed at opposite sides of the outside of the ring 11 are used for this purpose. Approximately in the center, each of these ribs 20 is provided with a perforation or hole which continues through the ring 11; the rib 20 is also provided at this point with a depression or groove 22 which continues in an upward direction in the plane of the rib 20 which is obliquely cut off and turned back to the inside. The bent end 23 of the leg 16 is located almost completely in the depression or groove 22 of the rib 20 so that the turning of the handle 13 is not hampered by any windings running over these ribs.

Thus, it will be seen that the carrying device of the present invention comprises a substantially cylindrical ring and a handle attached to this ring, wherein the height of the ring corresponds to the height of only a few piled up windings of the coiled material and wherein the ring is provided with radially outward projecting elements. The radially projecting elements of the ring may simply consist of a ring flange formed by raising the bottom edge of the ring.

When the carrying device supports a coil of coilable material, the ring is positioned inside the coil with a few (or a fraction) of the windings of the coiled material resting directly against the ring. The radially projecting elements of the ring are engaged between adjacent windings of the coil and these provide the supporting connection for the ring inside the coil.

The handle projects from one side of the coil. The ring is preferably located in the center bore of the coil in such a way that the top edge of the ring lies approximately in the same plane as the upper side of the coil and so that the turnability of the handle is not prevented. At the top edge of the ring, upward projecting lips or similar projections may be provided, which mainly protrude in an axial direction and to which the handle is attached. When carrying a coil by means of the handle of the carrying device of the present invention, the layers of the coil do not sag, apparently because of their mutual coherence despite the weight of wire coil beneath the ring.

The length or width of the radially projecting elements, which may consist of simply a ring flange, is preferably at least equal to the thickness of one layer of coiled material, thus allowing the projecting elements to engage far enough between the windings of the material in order to provide a firm fixation of the ring in the coil. In practice, the inside diameter of the ring will be approximately equal to the diameter of the mandrel of the winding machine, on which the coils are wound during their formation, so that the ring can be slipped beforehand on the mandrel of the winding machine. When winding a coil, at least a few windings of the first layer of the coil are wound directly on the ring and thereafter the next part of the winding process normally proceeds directly on the mandrel. After finishing the coil, the handle may be fixed to the ring and employed to remove the coil from the mandrel.

Inasmuch as the present invention is subject to many variations, modifications and changes in detail, it is intended that all matter contained in the foregoing description or shown in the accompanying drawings shall be interpreted as illustrative and not in a limiting sense.

What is claimed is:

1. A device adapted to carry a coil of barbed wire or the like having a predetermined inside diameter which comprises

a cylindrical ring having an outside diameter about the same as the inside diameter of said coil, said cylindrical ring having an axial height adapted to correspond to a fraction of the windings of the inner layer of said coil, at least one radial projection extending outwardly from one end of said ring a distance sufficient to support said coil thereon, said radial projection adapted to engage between adjacent windings of the inside surface of said coil, and a handle connected to said ring and adapted to carry said device,

said ring being provided at its other end with a pair of projecting lips to which said handle is movably connected.

2. A device adapted to carry a coil of barbed wire or the like having a predetermined inside diameter which comprises

a cylindrical ring having an outside diameter about the same as the inside diameter of said coil and being provided with a plurality of axial ribs, said cylindrical ring having an axial height adapted to correspond to a fraction of the windings of the inner layer of said coil, at least one radial projection extending outwardly from one end of said ring a distance sufficient to support said coil thereon, said radial projection adapted to engage between adjacent windings of the inside surface of said coil, and a handle connected to said ring and adapted to carry said device.

3. An article of manufacture comprising a cylindrical ring having a predetermined outside diameter,

at least one radial projection extending outwardly from one end of said ring a distance sufficient to support a coil of wire,

a coil of barbed wire having an inside diameter about the same as the outside diameter of said ring and supported on said radial projection, the outside diameter of said coil of barbed wire being greater than the outside diameter of said radial projection, said cylindrical ring having an axial height corresponding to a fraction of the windings of the inner layer of said coil,

said radial projection engaging between adjacent windings of the inside surface of said coil, and a handle connected to said ring and adapted to carry said device with said coil wound thereon.

4. The invention as defined in claim 3 wherein said radial projection is an annular flange integrally mounted on the bottom of said ring.

5. The invention as defined by claim 3 wherein the cylindrical ring and its radial projection are constructed of plastic.

6. The invention as defined by claim 3 wherein said handle is U-shaped and is adapted to engage in the central bore of a second coil of wire piled on top of said first coil of wire.

7. The invention as defined by claim 3 wherein said coil of barbed wire has an outside diameter in the range of about 30 to 40 cm., an inside diameter in the range of about 10 to 12 cm. and a height in the range of about 20 to 30 cm. and the axial height of said ring is about 2 cm. and the width of said radial projection is about 0.3 cm.
